ALEX MARCUS

BY

Chas. C. Gill

ATTORNEY

UNITED STATES PATENT OFFICE.

ALEX MARCUS, OF BROOKLYN, NEW YORK.

DESIGN FOR A POWDER-CLOTH.

55,391.

Specification for Design.

Patented June 1, 1920.

Application filed March 12, 1919. Serial No. 282,215. Term of patent 14 years.

To all whom it may concern:

Be it known that I, ALEX MARCUS, a citizen of the United States, residing at Brooklyn, in the county of Kings and State of New York, have invented a new, original, and ornamental Design for a Powder-Cloth, of which the following is a specification, reference being had to the accompanying drawings, forming a part thereof, and in which—

Figure 1 is a top view, and
Fig. 2 an edge view of a powder cloth embodying my design.

I claim:

The ornamental design for a powder cloth, as shown.

ALEX MARCUS.

Witnesses:

CHAS. C. GILL,
ARTHUR MARION.
